POLYPHASE TRANSFORMER TAP-CHANGING MECHANISM

Karl Bölte, Karlshorst, Germany, assignor to
 General Electric Company, a corporation of
 New York

Application February 8, 1937, Serial No. 124,733
 In Germany February 13, 1936

1 Claim. (Cl. 200—6)

My invention relates to polyphase transformer tap-changing mechanisms. In a polyphase transformer which has windings provided with tap connections and switches for varying the voltage ratio of the transformer, it is desirable that the switches be operated substantially simultaneously in order to prevent unbalance of the phase voltages for any appreciable period of time.

10 The general object of the present invention is to provide an improved polyphase tap-changing switch mechanism so arranged that the operation of any individual switch will automatically result in a substantial increase of the operating force applied to the remaining switches and instantly cause their operation. Thus, the time delay between the operation of the switches will be extremely brief and there will be no appreciable unbalance of the phase voltages.

20 The invention will be better understood from the following description taken in connection with the accompanying drawing in which Fig. 1 is a simplified view of a three-phase group of switches with their operating mechanism arranged in accordance with the invention, and Fig. 2 indicates the application of the tap-changing mechanism of Fig. 1 to a three-phase transformer.

30 The tap-changing mechanism is shown in the drawing as being enclosed in a switch casing 10 mounted on one side of the main casing of a three-phase transformer 11. The three windings 12, 13 and 14, which may be either the primary or secondary windings of the transformer, are provided with taps connected respectively to the fixed contacts of three tap switches 15, 16 and 17. The movable contacts of these three switches 15, 16 and 17 are operated respectively by individual shafts 18, 19 and 20 which are in turn operated through bevel gears by a common operating shaft 21. The three switches 15, 16 and 17 include spring connections 22, 23 and 24 interposed respectively between the common shaft 21 and the three movable contacts of the switches. A common spring connection 25 is also interposed in the common shaft 21 which of course may be operated by hand or from any suitable source of power, such as a motor.

When it is desired to change the voltage ratio 50 of the transformer, the three switches 15, 16 and 17 are operated by applying a torque to the outer

end of the common shaft 21. This torque, however, is opposed by the resistance of the switches so that increasing tensions of the spring connections 22, 23, 24 and 25 are produced. It is obvious, however, that the tension of any one of the spring connections 22, 23 and 24 is much smaller than that of the common spring connection 25. As the torque of the common shaft 21 increases, the torque of each of the shafts 18, 19 and 20 will of course increase until finally the resistance of one of the switches 15, 16 and 17 will be overcome sufficiently to operate its movable contact with a snap action. Suppose, for example, that the resistance of the switch 15 is the first to be overcome and that this switch 15 is the first one 15 to operate. The tension of the spring connection 22 will instantly decrease and its opposition to the torque of the common spring connection 25 will be suddenly reduced. This will result in a sudden and simultaneous increase in the tensions of both of the spring connections 23 and 24 and consequently in the torque applied to the switches 16 and 17 which are already about to be operated. This increased torque applied to these two switches 16 and 17 will therefore cause them to operate with extremely small time delay after the initial operation of the switch 15. In like manner, it is obvious that the operation of either of the switches 16 or 17 will automatically and instantly produce an increase in the torque applied to the other two switches and consequently result in their operation with substantially no time delay or unbalance of the phase voltages.

The invention has been explained by describing and illustrating a simple arrangement of polyphase tap switches with a switch operating mechanism arranged in accordance with the invention, but it will be obvious that changes may be made without departing from the spirit of the invention and the scope of the appended claim.

What I claim as new and desire to secure by Letters Patent of the United States, is:

The combination with a plurality of snap action tap switches for a polyphase transformer, of a common operating means including a spring connection for operating the switches, each switch including an individual spring connection between itself and said common spring connection.
